UNITED STATES PATENT OFFICE

124,055

DESIGN FOR A CROQUETTE MOLD

Ralph Arone, Minneapolis, Minn.

Application May 13, 1940, Serial No. 92,335

Term of patent 3½ years

To all whom it may concern:

Be it known that I, Ralph Arone, a citizen of the United States, residing at Minneapolis, in the county of Hennepin and State of Minnesota, have invented a new, original, and ornamental Design for a Croquette Mold, of which the following is a specification, reference being had to the accompanying drawing, forming part thereof.

Fig. 1 is a top plan view of a croquette mold embodying my design;

Fig. 2 is a view in end elevation as seen from the left of Fig. 1;

Fig. 3 is a view in side elevation as seen from the bottom of Fig. 1; and

Fig. 4 is a partial view in side elevation showing the side opposite that shown in Fig. 3.

I claim:

The ornamental design for a croquette mold, as shown.

RALPH ARONE.
